[57] ABSTRACT

There is disclosed a direct contact, water-nonsubmerged system for heating of a swimming pool by the transverse flowing of water into direct contact with a flowing heat source. In the specific practice, a source of swimming pool water is flowed onto a water dispersing surface containing a multiplicity of weep holes and then flowed through the weep holes into a heat source flowing transverse to the water flow through the weep holes.

SWIMMING POOL HEATER

THE INVENTION

This invention relates to a novel heating system for the effective heating of swimming pools. More particularly, this invention relates to a high thermal efficiency system for the heating of swimming pool water, in which the fuel combustion takes place at substantially atmospheric pressure.

Water heating has conventionally been accomplished generally in one of two ways:

One is by the direct heating of coils of thin-walled tubing or piping, through which the water to be heated passes. The coils are in a heated environment, such as a gas-fired chamber, and the coils may be so wound as to provide several passages of the water through the chamber in order to obtain maximum transfer of heat to the water through the usually thin walls of the tubing or piping. This heating method is generally described as the direct-fired method.

In another implementation of the direct-fired water heater, an external jacket of captive water surrounds the pipe through which heat is passed. The outer jacket of water is heated by the heat transferred from the pipe within.

A disadvantage of the above methods is that the gases of the firing burners normally have a moisture by-product generated therein from combustion. Generally the exhaust temperature and internal apparatus component temperatures in these systems must be kept high enough to prevent condensation internally. Exhaust temperatures of 400°F or higher are common. This limits the thermal efficiency of such systems.

A second general method comprises so-called submerged combustion heating. In submerged combustion apparatus, either a horizontal or vertical burner produces combustion gases in a chamber submerged in a heat transfer or primary liquid such that the combustion gases issue from the chamber into the primary liquid to form a turbulent mixture which passes through a heat exchanger, the combustion gases and liquid being separated after passage through the heat exchanger.

In another configuration the submerged combustion apparatus produces combustion gases directly in the swimming pool water, the combustion gases and pool water being separated near the surface of the pool.

Submerged combustion suffers from the disadvantage that the heated liquid dissolves part of the soluble components of the combustion products, especially carbon dioxide, sulphur dioxide, sulphur trioxide, oxygen and becomes corrosive as regards ordinary metals. Another disadvantage is the difficulty of making the apparatus work at high pressure, in view of the great bulk required in that case for the container which, having to withstand the pressure, must also comprise the considerable space occupied by the heated liquid and, moreover, contain the means needed to cause this liquid to enter and leave the pressurized container.

In accordance with this invention, there is provided a thermally economic and efficient, low-pressure combustion swimming pool system.

More particularly, this invention relates to the direct contact, water-nonsubmerged heating of a swimming pool whereby a supply of water from the swimming

pool is flowed into direct contact with a flowing heat source, the flow of water being transverse relative to that of the heat flow.

Reference is made to the drawings and FIGS. 1 to 4 thereon.

FIG. 1 represents one embodiment of this invention, utilizing a single layer of weep holes.

FIG. 2 represents a further embodiment of this invention, utilizing multiple layers of weep holes.

FIG. 3 is a view along Section 3—3 of FIG. 4.

FIG. 4 is a burner end view of FIG. 2.

In FIG. 1 there is shown a relatively elongated, single-layer swimming pool heater having an upper trough 16 and a lower trough 22, with sides 15a, 15b, ends 15c, 15d, water dispersing plate (and dividing layer) 17a containing weep holes 14, and a bottom pan 17b.

The heater is supported by brackets 20 attached to a swimming pool wall 26.

A source of swimming pool water 12 is applied via conduit 10 supported by bracket 11. The water flows as multiple streams 29 from the upper portion 16 through the water dispersing plate 17a via weep holes 14 into the lower trough 22 such that the water is heated by direct contact with hot gases and flame 28 emitted by burner 18 supported on bracket 19. The heated water 24 exits typically as a thin sheet, from the bottom trough 22 via the open portion of end 15d. The heated water is returned to the swimming pool by any convenient means.

In FIG. 2 there is shown a multi-level swimming pool heater (a stacked-folded variation of FIG. 1) supported on bracket 40 attached to a swimming pool wall 46, the heater having an upper section 33a, an intermediate section 33b, and bottom section 33c, with sides 36a, 36b, ends 36c, 36d, top water dispersing plate 42 having a lip portion 35a, intermediate water dispersing plate 37 having a lip portion 35b, bottom pan 41 having exit conduit 43, vertical dividing walls 47a, 47b, intermediate chimney 33e, and exit chimney 33d. A plurality of weep holes 34 are provided in water dispersing plates 42 and 37.

A source of swimming pool water 32 is flowed into the open upper section 33a from a conduit 30 supported by bracket 31. The water flows along a top water dispersing plate 42 and through the weep holes 34 into section 33b onto the intermediate water dispersing plate 37; then, through weep holes 34 into bottom section 33c onto the bottom pan 41. A burner 38 supported on a bracket 39 emits hot gas and flame 48 in a transverse direction relative to the flow of water 49 through the weep holes 34. The hot gas flows through the heater as indicated by the arrows 51; that is, the gas flows through the bottom section 33c in a first direction and then reverses its direction of flow around dividing wall 47b. The gas passes from the bottom section 33c upwardly through chimney portion 33e to the intermediate section 33b. The hot gas then flows in a first direction through intermediate section 33b and then reverses its direction of flow around dividing wall 47a. The gas exits from the heater via chimney 33d. The resulting heated water 44 exits from the heater via drain 43.

The water supply to and from the swimming pool may be continuous or discontinuous, depending upon the auxiliary equipment, such as pumps, holding tanks, etc.

The water flow from the pool may be split flow; e.g., a portion recycled from the filter directly back to the pool and the other portion supplied to the heater. Likewise, the water flow back to the pool can be split flow; e.g., part from the heater and part from another source.

The weep holes in each dividing layer may be of any shape or form such as perforations, slots, etc., with the size and number of holes being adjusted to handle the required flow of water. Each dividing layer may be provided with overflow baffles or like means to adjust the water level thereon and/or regulate or assist flow through the weep holes. Each dispersing plate or dividing layer may also be positioned at any appropriate angle so as to regulate or assist water flow. Likewise, the entire heater can be tilted to an angle to permit overflow of a portion of the water. Regardless of the angle(s) of the dividing layer or the entire heater, the water flow through the weep holes should be substantially transverse to the flow of heat.

The weep holes should be sufficiently remote from the burner tip or nozzle to keep substantial quantities of water from contacting the flame and to permit substantial fuel combustion such that interfering amounts of carbon monoxide are not formed. Thus, the weep holes should not be positioned directly above the burner tip or the flame emitted therefrom, but should be positioned downstream from the tip and flame. The weep holes may also be located adjacent to the sides of the flowing flame to cool; e.g., via a falling water film, the vertical sides and ends of the heater.

The cooling of the sides of the heater may be especially advantageous from the standpoints of safety, the conservation of the materials of construction, and increased thermal efficiency.

Any suitable fuel can be utilized in the practice hereof. Although solid fuels may be used, the most practical fuels are liquid or gas, especially hydrocarbons. The practice of this invention has the further advantage of low-pressure combustion; e.g., by use of a low pressure hydrocarbon gas at a pressure of about 6 to 7 inches of water with combustion at substantially atmospheric pressure.

Although only two weep hole layers are illustrated in FIG. 2, it is contemplated that additional layers can be employed.

The heated water is discharged from the heater at one or a multiplicity of exits. Such exits may be positioned at any level, in the sides, in the bottom, at either or both ends, etc.

The geometric configuration of the overall heater body; e.g., outer shell, may be of any suitable design; e.g., cylindrical, spherical, cubic, etc. Likewise, the geometric cross-section of each dividing layer; e.g., in a horizontal plane transverse to the water's downward flow, may be of any suitable design; e.g., square, rectangle, circle, ellipse, triangle, trapozoid, etc.

A variety of auxiliary equipment may be utilized in combination with this invention; that is, the heater may be a self-contained unit or may be integrated with other pool equipment, including not by way of limitation filters, holding tanks, control valves, burner blowers with or without air or oxygen assists, chimney eductors, burner blowers, etc., as well as combinations thereof. Thus, for example, a blower for the burner may be hydraulically driven by a head of water generated from the pool filter system.

We claim:

1. A nonsubmerged, direct contact process for heating a swimming pool which comprises withdrawing a supply of water from the pool, flowing the withdrawn water into the upper zone of a heating chamber having at least two zones, dispersing and gravity flowing the water from the upper zone through a multiplicity of weep holes into a lower zone into direct contact with a flowing heat source, the flow of the water being substantially transverse to the flow of the heat, withdrawing the heated water from the chamber and returning it to the pool, and gravity flowing a portion of the water from the upper zone to the lower zone as a thin film along inner walls of the chamber so as to cool such walls and increase the overall thermal efficiency of the process.

10 2. Apparatus for heating swimming pool water wherein the water is circulated from the pool and returned thereto, comprising a chamber having a bottom, side, and end walls, an opening formed in one end wall of said chamber adjacent the bottom thereof, a combustion burner, means mounting said burner in said opening with the flame therefrom sweeping generally horizontally toward an exhaust opening at the other end wall, at least one horizontal, water dispersing, plate spanning the length and width of said chamber and mounted above said opening in said one end wall, said dispersing plate having a plurality of water weep holes formed therethrough to provide a plurality of substantially vertical water streams in a pattern excluding the area immediately overlying the extent of the sweep of the combustion flame, means mounted on said chamber for feeding water onto the

15 30 upper surface of said dispersing plate and outlet means communicating with the upper surface of said bottom for draining heated water for return to the pool.

20 35 3. Apparatus according to claim 2 wherein means are provided on the chamber for mounting of the chamber to a swimming pool side.

40 4. Apparatus according to claim 2 wherein the dispersing plate contains weep holes adjacent to the chamber side and end walls so as to provide a falling water film thereon.

45 5. Apparatus according to claim 4 wherein the burner is a low pressure, gas burner.

60 6. A swimming pool water heater comprising a chamber, said chamber formed of a bottom, side, and end walls, a first horizontal perforate, water dispersing plate spanning the length and width of said chamber and positioned in an upper portion of said chamber, a second generally horizontal, perforate water dispersing plate spanning the length and width of said chamber and positioned below the first plate within said chamber, a vertical baffle extending from the bottom of said chamber to at least the level of said first dispersing plate, said vertical plate being joined to one end wall of said chamber and extending at least part of the length of said chamber, said dispersing plates and said vertical plate generally separating the interior of said chamber into four elongated sub-chambers, said one end wall of said chamber being open in the area between the bottom wall and the second dispersing plate, a combustible fuel burner mounted in the open area of said one end wall for directing a generally horizontal flame pattern toward the other end wall, said second dispersing plate being imperforate in the area overlying the flame pat-

50 55 65

tern from said burner and terminating short of the one end wall on the opposite side of said vertical plate, said first dispersing plate terminating short of said one end wall on the same side of said vertical plate as the burner, whereby heated gases from said burner will travel in series through the four sub-chambers of said chamber, and exhaust upwardly adjacent said one end wall after contacting the dispersed water and transferring a substantial portion of its heat to said water, means for discharging swimming pool water onto the 10

upper surface of said first dispersing plate and opening means formed in the bottom wall of said chamber for discharging heated water from the heater into the pool.

5 7. Apparatus according to claim 6, wherein the dispersing plate contains perforations near the chamber side and end walls so as to provide a falling water film thereon.

8. Apparatus according to claim 7 wherein the burner is a low-pressure, gas burner.
